PROTECTIVE GRATING

Filed Nov. 13, 1940

UNITED STATES PATENT OFFICE

2,292,954

PROTECTIVE GRATING

Frank V. Martin, Atlantic City, N. J.

Application November 13, 1940, Serial No. 365,509

17 Claims. (Cl. 109—29)

This invention relates to protective or deterrent gratings for windows, doors, lights and other vulnerable areas in the walls, roofs, floors, etc., of banks, warehouses, stores, dwellings, jails, barracks, hospitals, and other institutions, liable to attack for illegal entry of or secretive escape from the interiors guarded by the gratings.

More particularly, the present invention relates to a novel type of restraining bar for use in such gratings, wherein each or any desired number of the bars constituting the grating is of hollow or recessed construction and confines a bomb and detonator therefor adapted to be fired by bodily removing the bar from the grating, bending or sawing the bar or otherwise tampering with the bar.

While the bomb may be of any desired character to give audible or visible warning of an attempt at forcible entry or escape, as by loud detonation or flare, it preferably is of the gas type to emit, through suitable orifices exterior of the bar and communicating with the bomb chamber in the bar, a disabling or irritating gas such as the so-called "tear" gas employed by police for subduing or routing criminals or dispersing undesirable assemblages.

In the accompanying drawing:

Fig. 1 is an exterior view of a wall opening protected by a grating embodying restraining bars made and operable in accordance with the principles of the present invention;

Fig. 2 is a longitudinal sectional view of one of the bars of Fig. 1;

Fig. 3 is a cross section taken on the line 3—3, Fig. 2;

Fig. 4 is a cross section taken on the line 4—4, Fig. 2;

Fig. 5 is a longitudinal sectional view of one modified form of bar within the scope of the invention;

Fig. 6 illustrates another modification of the invention;

Fig. 7 illustrates a modification of a detail of the invention; and

Fig. 8 illustrates a special mounting for one of the restraining bars.

As shown in Fig. 1, a masonry, steel, or other wall, which is normally resistant to penetration by the forms of attack employed by the ordinary burglar or others attempting forcible entry, is shown at 1. The wall 1 is provided with an opening 2 fitted with a steel or wood frame 3 for window-sash 4 and 5, or a door, shutter, etc.

The opening 2 is further fitted with a grating 10 embodying a plurality of parallel restraining

bars 11, 11 made, installed, and operable in accordance with the principles of the present invention.

As shown in Fig. 2, each restraining bar 11 is composed of two sections 11a and 11b which, in this figure, are shown as telescoping one within the other as at 12, and provided with cooperating male and female threads whereby the two sections are removably secured together to form the single rigid bar structure 11.

The opposite ends respectively of each bar structure 11 are secured in any suitable manner to or in the upper and lower rails 3a and 3b of the frame 3, or directly in the adjacent upper and lower walls 2a, 2b of the opening 2 in the closure wall 1.

As shown in Fig. 2, the lower end 13 of the lower bar section 11a is slidably mounted in a socket 14 which, in turn, is secured by screws 15 to the sill 3b of the frame 3.

The upper end 16 of the upper section 11b of each bar structure 11 is slidably or freely mounted in a socket 17 secured to the top rail 3a of the frame 3 by screws 18.

The ends 13 and 16 of the lower and upper sections 11a, 11b are externally threaded to show above and below the sockets 14 and 17 respectively, merely for deceptive purposes to mislead those planning to tamper with the bars.

In metal window-frames, the top rail 3a, bottom rail 3b, and side rails 3c, 3c are normally welded together and constitute a rigid marginal frame for the grating of which the restraining bars 11 constitute the intermediate part. Where wooden window-frames are employed, the grating may include a rigid marginal metal frame comprising a top rail 3a, bottom rail 3b and side rails 3c, 3c separate and distinct from the window-frame and securely anchored in the wall opening 2 inside or outside the window-frame 3, as desired. In the case of door openings the grating formed with the rigid marginal frame members 3a, 3b and 3c and bars 11, 11 would be hinged and provided with suitable locking devices.

In that form of the invention shown in Fig. 2, the upper edge 19 of the lower section 11a of each bar structure 11 provides an annular shoulder support for a bomb-carrier 20. In the present instance, the bomb-carrier 20 is in the form of an annular split ring having inturned ends 21, 21 (Fig. 3) which are pressed into the sides of a bomb unit 22, adjacent the lower end thereof, leaving a gap between said ends which forms a longitudinal gas passage 23. The top edge

of the holder 20 is beveled to provide a circumferential gas channel 24 which communicates with the passage 23.

The bomb unit 22 is confined within an inner sleeve 25 having its lower end resting on the upper beveled end of the split ring 29. The sleeve 25 has a more or less free, loose fit in the tube section 11b, in order that any attempt to saw through the bar will result in the saw teeth engaging the outer surface of the sleeve 25, after one side of the outer shell 11b has been sawed through, causing the sleeve 25 to revolve within the shell 11b and resist penetration by the saw teeth, at the same time preventing the saw teeth from penetrating the outer tube or shell 11b further.

The sleeve 25 is provided with a series of longitudinal indentations 26 which bear against the bomb 22 (Fig. 4) and provide gas channels 27, 27, between the sleeve 25 and the outer tube 11b, and channels 28, 28, between the bomb 22 and sleeve 25. The lower ends of the channels 27, 28 communicate with the circumferential channel 24 and the upper ends of these channels 27, 28 communicate with the interior of the tube section 11b, above the bomb 22.

The upper end of the rotatable sleeve 25 abuts the lower end of a second rotatable inner sleeve 29, which, under the above-noted circumstances, will roll or revolve under attack by a saw. Secured in the lower end of the upper inner sleeve 29 is a cartridge support 30. The support 30 is in the form of an inverted cup with its annular side wall 31 in contact with the inner surface of the upper rotary sleeve 29 and secured thereto in any suitable manner. In the present instance, the annular wall 31 of the cup 30 is provided with openings 32 into which small protuberances 33 of the metal of the sleeve 30 are pressed.

The head 34 of the cartridge-carrier 30 is bored at 35 for reception of the body portion 36 of a blank cartridge 37, the rim 38 of which rests on the upper surface of the carrier head 34. The lower or wad-end of cartridge 37 lies directly above the upper end of the bomb unit 22, in order that the flash from the powder in the cartridge 37, when exploded, will ignite the upper end of the bomb 22.

The cartridge 37 is fired by a spring-loaded firing pin 40, the shank 41 of which is slidably mounted, for axial movement, in a central bore 42 of a bearing plug 43. This plug may be secured in the upper end of the upper section 11b of the bar 11, as, for example, by plug 43 having a driving fit in the tube 11b.

The firing pin 40 is provided with an adjustable collar or nut 44 between which and the under side of the plug 43 is confined a firing spring 45. The spring 45 encircles the shank 41 of the firing pin 40.

Adjacent its upper end, the shank 41 is circumferentially grooved, at 46, for reception of a rounded semispherical inner end of a trigger pin 47. This pin 47 is slidably mounted in a transverse bore 48 in the plug 43 and in an axial extension thereof formed in the tube section 11b.

The trigger pin 47 is of such length that, when the inner rounded end thereof is seated in the root of the annular concave groove 46, the outer end is flush with the outer surface of the upper tubular section 11b of the bar 11 and rests against the inner surface 49 of the plain bore 75

of the socket 17, thus the firing pin 40 is normally held in a "cocked" position.

The lower end of the socket 17 is counterbored at 50 to provide an annular recess therein and the upper end of the socket is likewise counterbored or beveled to provide an annular recess 51 in the socket 17. Under any circumstances, by which relative axial movement is effected between the upper section 11b of the bar 11 and the socket 17, to the extent wherein the outer end of the trigger pin 47 is free to move into either of the annular recesses 50 or 51 of the socket 17, the pressure exerted by the spring 45 to move firing pin 40 axially will cause the concave groove 46, acting against the round inner end of the trigger pin 47, to force the trigger outwardly, thereby releasing the firing pin 40.

The spring 45 drives the firing pin 40 down into contact with the detonator cap of the cartridge 37, thereby firing the cartridge 37 and causing the flash of the exploded powder to ignite the upper end of the bomb unit 22. The bomb unit 22, as previously noted, is of the gas-generating or exuding type which are readily obtainable on the market by qualified users. The burning bomb 22 generates high gas pressure in the tubular bar below the inverted cup 30. This gas passes down through the gas channels 27, 28, 24 and 23, under the bottom of the bomb 22 into the lower section 11a of the bar 11 and exhausts through apertures 52, 52 therein, into the atmosphere in and around the space in which the bar 11 is located.

Ordinarily, the generation of gas by the burning bomb 22 is so rapid that it will take effect upon the person tampering with the bar before complete removal of the bar can be accomplished. The gas, being of the irritant type, i. e., inducive of rapid and excessive secretion by the lachrymal glands, temporarily blinds or disables the tamperer, while the report of the exploding cartridge provides an audible alarm. Thus, while the bars 11, 11 may not form an absolutely impregnable barrier, they will serve individually and collectively as a deterrent to any one attempting to remove the obstacle presented by the bars, while the sounding of the alarm and the disabling of the tamperer may result in capture at or near the scene.

To one familiar with the interior construction and operation of the mechanism contained in the bar 11, such as an authorized service man, the bars 11 may be removed, to replace the bombs 22 and cartridges 37 periodically with fresh ones, by first securing the socket 17 to the upper end of the tube section 11b as by a suitable split clamp engageable with each to prevent relative axial movement therebetween; then removing the fastenings 18 and 19 of the sockets 17 and 14 respectively, after which the bar 11 may be removed bodily from the opening 2.

After removal of the bar 11, the section 11a may be unscrewed from the section 11b at 12. The bomb 22 and its carrier 29, the sleeve 25 and the sleeve 29, with the cartridge support 30 therein, may then be removed from the section 11b. Reassembly may be readily effected by reversing this order.

If desired, the restraining bars may be made in one piece, as shown in Fig. 5 at 11c, and with the interior elements, i. e., the unit 20—22 and the sleeves 25 and 29 supported by a perforated, readily rotatable tube 53 provided with spacer rings 54, 54 to keep the tube 53 spaced from the

tube 11c to permit the gas to flow from the interior of the tube 53 through its perforations 55 and out of the perforations 45a in the outer tube 11c.

In that form of the invention shown in Fig. 6, the upper end of the lower tube section 11d and the lower end of the upper tube section 11e are confined in a telescoping outer short tube section 12a. The bomb 22 and detonator cartridge 37 are replaced by a cartridge 22a which contains the tear gas generating substance and also a detonator cap 31a.

The rim 38a of the gas cartridge 22a rests on the upper edge 19a of the lower tube section 11d, within the telescoping coupling sleeve 12a, and the lower edge of the upper tube section 11e is disposed above the rim 38a. The sleeve 12a is preferably secured rigidly to the lower tube section 11d although it may be secured to the upper tube section or both without departing from the spirit of the invention.

The upper section 11e contains the firing pin and trigger mechanism and the lower section is provided with the gas outlets, the same as in the structure of Fig. 2. If desired, these sections may also contain the rotary inner sleeves like the sleeves 29, 25 and 53 of Fig. 5.

During assembly, the firing pin is moved to cocked position in the plug 43a. The screw 56 is then used as a set screw to hold the firing pin 41a in place. The plug 43a is then placed in the tube 11f. The trigger 47a is then inserted with its inner end in the groove 46a of the firing pin and its outer end flush with the outside of the tube 11f, in which position it is then retained by any suitable form of temporary clamp or split sleeve placed around the tube. The screw 56 is then backed out until its outer end is flush with the outside of the tube 11f, at which time its inner end is clear of the firing pin 41a. The tube is then slipped into the socket 17a until the trigger pin 47a is engaged by the bearing surface 49a of said socket, the temporary clamp or sleeve at the same time being moved down on the tube 11f and from which it is then removed leaving the trigger pin 47a under control of the bearing surface 49a of the socket 17a.

In the case of skylights and the like, the trigger and bomb containing end of the bar 11g (Fig. 8) would fit in a socket 17b provided with a pivot lug or lugs 60 which would cooperate with a pivot lug or lugs 57 on a bracket 58, through a rivet 59 which functions as the pivot between the two, so that the bar 11g can swing from a normal horizontal position to a vertical position, under its own weight, and slip out of the socket 17b to release the trigger if and when the bar is sawed through intermediate its ends, or if the opposite end of the bar is forced out of its socket, which latter may be of either the rigid type or the pivoted type, as desired.

In order to force the upper end 16 of the upper section 11b of the bar 11 out of the socket 17, in event of a lower part of the bar being removed by sawing, for example, and thereby assure release of the trigger 47, a spring 60 (Fig. 2) is inserted between the upper end of the plug 43 and the under side of the window frame, etc., to which the socket 17 is secured, whereby any part of the bar left hanging in the socket will be forced out of the socket and permit the trigger 47 to move outwardly and release the firing pin 41 to effect discharge of the detonator 36 and consequent ignition of the bomb 22.

I claim:

1. A hollow protective grating bar containing a detonator and means for discharging said detonator, and means external of said bar for supporting said bar and retaining said discharging means normally inactive.
2. A hollow protective grating bar containing a gas generating unit and means for starting generation of gas thereby, and means external of said bar for supporting said bar and retaining said starting means normally inactive.
3. A hollow protective grating bar containing a gas generating unit, a detonator for starting generation of gas by said unit and means for discharging said detonator, and means external of said bar for supporting said bar and retaining said discharging means inactive.
4. A hollow protective grating bar containing a gas generating unit, a detonator for starting generation of gas by said unit and a spring-loaded trigger for discharging said detonator, and means external of said bar for supporting said bar and retaining said trigger normally in a cocked position.
5. A hollow protective grating bar enclosing a detonator and a spring-loaded firing pin therefor, a retaining socket embracing one end of the bar, and a trigger carried by the bar and normally engaged by the socket for holding the firing pin in a cocked position.
6. A hollow perforated protective grating bar enclosing a gas generating bomb with a detonator and a spring-loaded firing pin therefor, a retaining socket embracing one end of the bar, and a trigger carried by the bar and normally engaged by the socket for holding the firing pin in a cocked position.
7. A hollow protective grating bar enclosing a detonator and a spring-loaded firing pin therefor, a retaining socket embracing one end of the bar, a trigger carried by the bar and normally engaged by the socket for holding the firing pin in a cocked position, and an inner sleeve rotatable within the hollow bar around the detonator to afford protection for the detonator against transverse sawing of the bar.
8. A hollow perforated protective grating bar enclosing a gas generating bomb with a detonator and a spring-loaded firing pin therefor, a retaining socket embracing one end of the bar, a trigger carried by the bar and normally engaged by the socket for holding the firing pin in a cocked position, and an inner sleeve rotatable within the hollow bar around said bomb to afford protection for the bomb against transverse sawing of the bar.
9. A hollow perforated protective grating bar enclosing a gas generating bomb with a detonator and a spring-loaded firing pin therefor, a retaining socket embracing one end of the bar, a trigger carried by the bar and normally engaged by the socket for holding the firing pin in a cocked position, an inner sleeve rotatable within the hollow bar around said bomb and the detonator to resist transverse sawing of the bar, and a support for the detonator secured in the inner sleeve adjacent one end of the bomb.
10. A hollow protective grating bar enclosing a detonator and a spring-loaded firing pin axially aligned with the bar and the detonator, a plug rigidly mounted in the bar as an integral part thereof and affording an axial sliding bearing for the firing pin, a trigger pin slidably mounted in the plug for axial movement transversely thereof, a circumferential groove in the

firing pin for reception of the inner end of the trigger pin, and a socket embracing the bar and normally engaging the outer end of the trigger pin to hold the firing pin in a cocked position.

11. A hollow protective grating bar, a socket, an annular bearing surface formed in the socket and embracing the bar adjacent one end thereof, a detonator and means for firing said detonator enclosed in the bar, said firing means including a radially projectable element carried by the bar and normally retained substantially flush with the exterior surface of the bar by said annular bearing surface of the socket, said element being releasable from said bearing surface to fire said detonator by axial relative movement between the bar and the socket.

12. A hollow protective grating bar, containing a detonator and means for firing the detonator including an element having a portion projectable radially beyond the exterior surface of the bar, a socket embracing the bar adjacent one end thereof, an annular bearing surface formed on the interior of the socket and normally maintaining said projectable element substantially flush with said exterior surface of the bar, and a circular recess in the socket adjacent and parallel to said annular bearing surface to provide for radial movement of said element to fire said detonator upon relative axial movement between the bar and the socket.

13. A hollow protective grating bar, containing a detonator and means for firing the detonator including an element having a portion projectable radially beyond the exterior surface of the bar, a socket embracing the bar adjacent one end thereof, an annular bearing surface formed on the interior of the socket and normally maintaining said projectable element substantially flush with said exterior surface of the bar, and a circular recess in the socket adjacent and parallel to said annular bearing surface at each side of said annular bearing surface in the direction of the axis of the bar to provide for radial movement of said element to fire said detonator upon relative axial movement in either direction between the bar and the socket.

14. A hollow protective grating bar, a socket embracing the bar adjacent one end thereof, a detonator and means for firing said detonator

enclosed in the bar, said means including a radially projectable element normally retained substantially flush with the exterior surface of the bar by the socket, said element being releasable from said socket to fire said detonator by axial relative movement between the bar and the socket, and means for pivotally supporting said socket for swinging movement about an axis at right angles to the axis of the bar to afford release of the bar from the socket.

15. A hollow protective grating bar composed of two axially aligned sections arranged with adjacent ends of said sections in telescoping relation to each other, a detonator having support in said bar for replacement by separating said telescoping sections of the bar, supports for the opposite ends respectively of the bar, and means carried by the bar and controlled by one of said supports for normally firing said detonator upon effecting axial movement between the bar and the support controlling the detonator firing means.

16. A hollow protective grating bar composed of two axially aligned sections arranged with adjacent ends of said sections in telescoping relation to each other, a gas generating bomb and a detonator for firing said bomb having support in said bar for replacement by separating said telescoping sections of the bar, supports for the opposite ends respectively of the bar, and means carried by the bar and controlled by one of said supports for normally firing said detonator upon effecting axial movement between the bar and the support controlling the detonator firing means.

17. A hollow protective grating bar, means supporting said bar at opposite ends respectively thereof including a socket element embracing one end of the bar, a detonator and firing means therefor enclosed within said bar and including a trigger element projecting to the exterior of the bar, said trigger being held in cocked position by said socket for release by relative axial movement between said socket and the portion of the bar embraced thereby, and means for forcibly effecting said relative axial movement upon removal of any portion of the bar intermediate said end supports.

FRANK V. MARTIN.
